(57) CLAIM

The ornamental design for a gift box arrangement for socks and accessories, as shown and described.

DESCRIPTION

FIG. 1 is a top, side perspective view of a gift box arrangement for socks and accessories showing my new design; FIG. 2 is a top plan view thereof;

FIG. 3 is a left side elevational view thereof;

FIG. 4 is a right side elevational view thereof;

FIG. 5 is a front elevational view thereof;

FIG. 6 is a back elevational view thereof; and,

FIG. 7 is a top, perspective section view taken along lines 7-7 of FIG. 1.

The broken line showing of the gift box arrangement represents unclaimed subject matter and forms no part of the claimed design.
